United States Patent Office

Des. 180,766
Patented Aug. 13, 1957

180,766

ROOF VENTILATOR, OR SIMILAR ARTICLE

Hyman Coutin, Los Angeles, Calif.

Application April 18, 1955, Serial No. 35,546

Term of patent 14 years

(Cl. D62—3)

Fig. 1.

Fig. 2.

Fig. 3.

Figure 1 is a top plan view of a roof ventilator embodying my new design;

Fig. 2 is a side elevational view of the ventilator; and Fig. 3 is a bottom plan view thereof.

I claim:

The ornamental design for a roof ventilator, or similar article, as shown.
